United States Patent Office

Des. 203,074
Patented Nov. 30, 1965

203,074

BOTTLE OR SIMILAR ARTICLE

Robert Adell, 7500 Intervale Ave., Detroit, Mich.

Filed Oct. 20, 1964, Ser. No. 82,252

Term of patent 14 years

(Cl. D58—6)

FIG. 1 is an elevational view of a bottle embodying my new design;

FIG. 2 is a top view plan thereof;

FIG. 3 is a bottom view plan thereof;

FIG. 4 is a transverse sectional view of the bottle taken in the direction of the arrows on the horizontal section plane passed through the line 4—4 of FIG. 1;

FIG. 5 is a fragmentary sectional view with its middle portion broken away, said view being taken in the direction of the arrows on the section plane passed through the section line 5—5 of FIG. 4;

FIG. 6 is a fragmentary sectional view taken in the direction of the arrows on the vertical section plane passed through the section line 6—6 of FIG. 1.

I claim:

The ornamental design for a bottle or similar article, as shown.
